(57) **CLAIM**

The ornamental design of a telescoping eating utensil, as shown and described.

DESCRIPTION

FIG. 1 is a perspective view from above of my telescoping eating utensil design;

FIG. 2 is a perspective view from above of my telescoping eating utensil design;

FIG. 3 is a plan view of my telescoping eating utensil design;

FIG. 4 is a bottom view of my telescoping eating utensil design;

FIG. 5 is a left side elevation view of my telescoping eating utensil design, with the right side elevation view being a mirror image thereof;

FIG. 6 is a front view of my telescoping eating utensil design; and,

FIG. 7 is a back view of my telescoping eating utensil design. It is to be understood that the broken lines are for illustrative purposes only and form no part of the claimed design.
